The ornamental design for a bracket for securing accessories to an internal combustion engine, as shown and described.

DESCRIPTION

FIG. 1 is a perspective view of the bracket for securing accessories to an internal combustion engine of the present invention;

FIG. 2 is a perspective view of the opposite side thereof;

FIG. 3 is a front elevational view thereof;

FIG. 4 is a rear elevational view thereof;

FIG. 5 is a left-side elevational view thereof; and,

FIG. 6 is a right-side elevational view thereof.

FIG. 1

FIG. 2

FIG. 3

FIG. 4

FIG. 5

FIG. 6
